N. O. LINDSTROM.

ELECTRIC ELEVATOR.

(Application filed Nov. 9, 1901.)

(No Model.)

UNITED STATES PATENT OFFICE.

NIIS O. LINDSTROM, OF NEW YORK, N. Y., ASSIGNOR TO ALONZO B. SEE
AND WALTER L. TYLER, OF BROOKLYN, NEW YORK.

ELECTRIC ELEVATOR.

SPECIFICATION forming part of Letters Patent No. 693,038, dated February 11, 1902.

Application filed November 9, 1901. Serial No. 81,665. (No model.)

To all whom it may concern:

Be it known that I, NILS O. LINDSTROM, a citizen of the United States, residing at the city of New York, in the borough of Queens and State of New York, have invented certain new and useful Improvements in Electric Elevators, of which the following is a full, clear, and exact description.

This invention relates to the control of electric elevators. A preferred method of operating electric elevators is to provide a counterweight for the car which is heavier than the car itself, but which may become overbalanced by the weight of the passengers, since this method reduces the average work upon the motor. In operating such an elevator it sometimes happens that the counterweight lifts the car, in which case the driving-motor is itself driven and becomes a generator, sending current out to the line, while at other times the relative weights may be so adjusted by the number of passengers that the machine acts as a motor to either lift the car or lift the counterweight. In any case there is no certain means of indicating to the attendant in the car under what condition the actuating-machine is running at any particular time, and he therefore is not in a position to select what kind of regulating means shall be used in a given instance to alter the speed of the machine. For instance, if the machine is running as a motor its speed could be reduced by throwing resistance into the circuit; but if the machine happened to be running as a generator the resistance thrown in would increase its speed.

In slow-speed elevators it is seldom necessary to provide more than one speed for actuating the machine, as the brake can be relied upon to graduate a stop sufficiently to avoid a shock, and accurate stops at landings are easily accomplished; but in high-speed elevators it is essential that the speed of the actuating-machine be reduced before stopping at a landing by some other means than a brake, as the action of the brake on a car traveling at a high speed would inflict a serious shock on the car and its load. Furthermore, an accurate stop at a landing cannot usually be accomplished when a car is running at high speed without first slowing down

to a certain extent. Hence for high-speed overcounterweighted elevators it is desirable to provide means for automatically controlling the speed of the actuating-machine regardless of whether it is running as a motor or as a generator and which are under the perfect control of the attendant in the car, whereby he will be able to increase or reduce speed at will and without causing the car to move irregularly or by shocks and jumps. To accomplish this object, I have provided an actuating electric machine for the elevator having two armature-circuits, one of which is the regular working or driving circuit supplied from a suitable source of electricity through a commutator and the other is a closed circuit in which a current is generated whenever the machine is driven and which is connected through a second commutator with an external local circuit containing certain resistances. The current generated in the short circuit has a killing effect upon the driving-circuit and is always in opposition thereto. A resistance is provided in each circuit whereby their relative effects can be controlled. A second resistance is also placed in each circuit, which is under the control of the current in the other circuit, which provides a still further sensitiveness of action and a wider range of graduation of speeds and a saving of current. My invention also comprehends the control of such an actuating-machine and its resistances from the car and through pneumatic apparatus which responds to the movements of the actuating-handle in the car and causes a gradual change in speed in exact proportion to the extent of movement of the actuating-handle.

In the accompanying drawings, Figure 1 is a conventional plan of the complete elevator system; and Fig. 2 is a similar representation of the starting, stopping, and reversing switch.

A indicates the elevator-car; B, a counterweight heavier than the car, but lighter than the car when it is fully loaded. The cord a, sustaining the car and counterweight, passes over suitable guide-sheaves to a winding-drum D on the shaft of or otherwise driven by an electric motor C. The armature of the motor C is wound with two circuits inde-

pendent of each other and represented by the respective commutators c and c' . The brushes of commutator c are indicated by 1 and 2 and those of commutator c' by 3 and 4. The 5 main-supply circuit is indicated by the plus and minus signs. From one side of this circuit the wire 5 leads through a make, break, and reversing switch e to a solenoid S , thence to the terminals of rheostat r' , thence by 10 wire 6 to the brush 2, through the driving-circuit of the armature, brush 1, wire 7, rheostat R , wire 8 to the minus main. The second circuit of the armature is a closed short circuit, as follows: from brush 3 by wire 9 15 to solenoid S' , wire 10 to rheostat r , wire 11 to rheostat R' , and wire 12 to brush 4. The core of solenoid S carries a contact-piece s , which when the solenoid is energized traverses the contacts of rheostat r' and cuts the 20 resistance into the short circuit of the motor. The core of solenoid S' is similarly connected to a contact s' , which when the solenoid is energized sufficiently traverses the contacts of rheostat r and cuts resistance into the 25 main circuit of the motor. It will thus be seen that the current flowing in one of the motor-circuits controls the resistance in the other circuit to a certain extent. The rheostats R and R' are arranged with their contacts adjacent 30 to each other, so that they can be controlled by a single traveler r^2 , attached to rod r^3 . The traveler carries bridging-contacts 13 and 14, which pass over the respective contacts of the two rheostats. The connections of the 35 circuit-wires 7 and 8 with the terminals of the rheostat R and those of the wires 11 and 12 with the rheostat R' are such that when the traveler r^2 rises resistance is cut out of the main circuit and cut into the closed circuit. 40 The rod r^3 connects with a pivoted lever r^4 , which in turn connects with another rod f , attached to the end of air-cylinder F . This cylinder contains a fixed piston f' , attached to the base f^2 , so that when pressure is admitted above the piston the cylinder is caused 45 to rise or move instead of the piston. Adjacent to the cylinder and preferably formed in the same casting is an air-chamber g , supplied with compressed air or other fluid by pipe g' . This chamber communicates with the upper part of the cylinder through a port g^2 . In the upper part of the chamber g is fitted a piston-valve h , which when above the port admits pressure into the cylinder, when 50 opposite the port retains the pressure therein, and when below the port opens communication from the cylinder to the atmosphere through the upper open end of chamber g . The valve h is attached to a rod h' , adapted 55 to be raised and lowered by the oscillation of a lever i , pivoted at i^2 and to which said rod is connected. The lever is oscillated by means of a roller or lug i^2 , which it carries and which projects into a groove j in a plate j . 60 65 This groove is made up of a horizontal portion and two downwardly-inclined end portions. While the roller is in a horizontal por-

tion of the groove the valve is held stationary, and when the roller is forced into either of the inclined portions of the groove the valve is raised to admit pressure into the cylinder, and when the roller traverses the inclined portions of the groove toward the horizontal portion valve h is moved below the port and allows the pressure to escape from the cylinder. The roller is caused to traverse the groove by reciprocating the plate j , and this is accomplished from the elevator-car. The plate is attached to a rod k , connected to a double bell-crank k' . From each end of the bell-crank a cord l leads over suitable guide-sheaves and around a drum or sheave p in the car. By rotating the drum or wheel p in one direction the bell-crank is caused to tilt and move the rod k in a corresponding direction. A reverse movement of the controller p gives a reverse movement of the rod k . The rod k also controls a valve device for pneumatically operating the main switches and the brake. The rod passes through an open-ended cylinder and inside thereof is provided with two tight-fitting pistons k^2 and k^3 . A pipe leads to the middle of the cylinder between the pistons and supplies fluid-pressure. Outside and beyond each valve pipes q and q' lead to suitable fluid-motors o and o' for throwing the main reversing-switch e . (Shown in Fig. 2.)

It will be understood that when air is admitted to the pipe q current will be turned on at the switch e in the proper direction to start the elevator upward, while when air is admitted to the pipe q' current is admitted in the proper direction to start the elevator downward. The two pipes q and q' are connected together by a cross-pipe q^2 , containing a valve-chamber q^3 , from which another pipe q^4 leads off to a fluid-motor for operating the brake, the latter not being shown, since it forms no part of the present invention. The valve-chamber q^3 contains a double valve q^5 , which when pressure enters the chamber from pipe q moves over and closes pipe q' and allows the air from pipe q to enter pipe q^4 , and when air enters the chamber from pipe q' the valve is forced over and closes pipe q and allows pressure to enter the brake-pipe from q' . Hence the brake is operated when pressure is admitted to either of the pipes q or q' .

In the normal condition of the apparatus with the elevator stationary both pipes q and q' are open to the atmosphere, as shown. The roller i^2 is in the horizontal portion of the groove g^2 , valve h is in front of the port g^2 , cylinder F is in its lowest position, and the solenoids S and S' are deenergized. In this state let it be assumed that the elevator is to be started upward under such conditions of load and counterweight that the motor must do work. By operating the controller p in the car the assistant moves the rod k to the right. The first result of this is to admit pressure to the pipe q and to the pipe q^4 , which closes the main switch in the direction to start the car.

upward and releases the brake. The motor draws sufficient current from the main circuit to lift the load. If the assistant desires to increase the speed, he will continue the motion of the controller in the same direction. This will cause the roller r^2 to enter one of the inclined portions of the groove j' , which will lift the valve h a distance depending upon the movement of rod k . Pressure will enter cylinder F and it will rise until the port is again closed by coming opposite the valve h in its new position. The upward movement of the cylinder causes traveler r^2 to cut out a corresponding portion of the resistance R. Consequently the motor gets more current and accelerates its speed. When the motor started in the first instance, the entire resistance R' was out of the closed circuit of the motor, but r' was thrown in by solenoid S, so that the killing effect of the closed circuit was small and the motor was not required to draw excessive current at starting. When the speed was increased by raising the traveler r^2 , the resistance R' was cut into the closed circuit at the same time that the resistance R was cut out of the main circuit. Consequently an increase of current which would naturally be generated in the closed circuit by the increased speed due to cutting out the resistance in the main circuit is prevented by the insertion of resistance R', and the motor is allowed to run at the required increased speed. At the highest speed the contact 14 runs onto the isolated contacts at the limit of the rheostat and opens the short circuit, which renders it entirely ineffectual. This increase of speed can be made as gradual as desired by the extent of movement of the valve h . It will be seen that when the valve moves upward a given distance the cylinder follows it to the same distance and there stops, and the speed of the machine is increased only to a corresponding extent. A further movement of the valve gives additional speed, and so on, to the limit. If the valve were thrown to the full limit in the first instance, the machine would get up its full speed as rapidly as the construction would allow. This would not be too rapidly for the comfort and safety of the load, because the size of the port g^2 can be regulated to admit pressure to the cylinder at the proper rate to secure the desired result. Both the valve h and the cylinder F are weighted, by means of the weights w and w' , to steady or retard all movements thereof, and the weight w is sufficient to balance the pressure on the valve. The solenoid S is wound so that it will not lift its core until some of the resistance R is cut out. When it does operate, the resistance r' is thrown into the killing-circuit. Thus the killing-circuit under this condition will be rendered less effective and the motor will start the load easily. The operation so far described relates to the condition when the motor does work either in

lifting the loaded car in going up or in lifting the counterweight in going down.

The operation will now be described when the actuating-machine is driven as a dynamo either by the maximum-loaded elevator coming down or the minimum load going up. When the circuit is closed to start the elevator, the brake is at the same time released, as before, whereupon the counterweight or the load drives the machine as a dynamo. At the start the closed circuit of the machine contains no resistance, and in consequence the speed of the machine is retarded by the rapid building up of current in the short circuit. The speed at the start is therefore normal or the same as when the machine starts under a load. To increase the speed, the rod k is moved farther in the same direction, as before, and the traveler rises, throwing resistance R' into the closed circuit, cutting down the current therein, and permitting the machine to be driven faster. The speed can thus be increased by degrees in the same manner as before, and the corresponding decrease of speed is accomplished by the reverse movement of the control. In starting up the machine under its driven condition all of the resistance R is in the main circuit, and the resistance r' is immediately cut in by the heavy current generated in the closed circuit and acting on solenoid S. Hence a gradual start is assured because the motor receives little, if any, current from the main circuit; but as the traveler r^2 moves upward the speed is increased both by the removal of resistance R and the insertion of R' until the highest speed is reached, when the traveler arrives at the top of the row of contacts and opens the closed circuit by passing onto the isolated contacts shown. In this system of control, where the two circuits are worked against each other, a very smooth-running electric elevator is obtained, the motion being more nearly like that of the hydraulic elevator than has been possible heretofore.

The action of the pneumatic devices materially aids in this smoothness of operation also, because quick movement of the valve h , while responded to in equal extent, is at more deliberate speed and the operator is unable to impart jerks and shocks to the car.

Having described my invention, I claim—

1. In an electric elevator, an actuating-machine having two armature-circuits acting in opposition to each other, in combination with means in the elevator-car for controlling the current in each circuit.
2. In an electric elevator, an actuating-machine having two armature-circuits acting in opposition to each other, a rheostat in each circuit and means for simultaneously throwing one rheostat out of its circuit and the other into its circuit, substantially as described.
3. In an electric elevator, an actuating-machine having two armature-circuits acting in

opposition to each other, a rheostat in each circuit and means in the elevator-car for simultaneously throwing one rheostat out of its circuit and the other into its circuit, substantially as described.

4. In an electric elevator, an actuating-machine having a main working circuit and a second circuit in which a current is generated by the rotation of the machine, in combination with means in the elevator-car for controlling the current generated in the second circuit, substantially as described.

5. In an electric elevator, an actuating-machine having two armature-circuits acting in opposition to each other, a rheostat for each circuit and means whereby current flowing in one circuit will throw one of the rheostats into the other circuit, substantially as described.

20 6. In an electric elevator, an actuating-machine having two armature-circuits acting in opposition to each other, a rheostat for each circuit and means whereby current flowing in one circuit will throw one of the rheostats into the other circuit, in combination with a second resistance for each circuit under control from the elevator-car.

7. In an electric elevator, an actuating-machine having two armature-circuits acting in opposition to each other, a rheostat for each circuit and means whereby current flowing in one circuit will throw one of the rheostats into the other circuit, in combination with a second resistance for each circuit, and means

35 in the elevator-car for simultaneously cutting out one of the second resistances and

cutting in the other, substantially as described.

8. In an electric elevator, the combination of an electric actuating-machine, a controlling-rheostat therefor, a fluid-motor adapted to actuate the rheostat, a valve for the motor actuated from the elevator-car, and means whereby the stroke of the motor will correspond to the stroke of the valve.

40 9. In an electric elevator, the combination of a fluid-motor, a valve therefor having a movement variable at will from the elevator-car, a movable part of said motor having a stroke equal and corresponding to that of the valve, a rheostat for an actuating-machine controlled by said motor, and an actuating-machine, substantially as described.

10. In an electric elevator, an actuating-machine having two armature-circuits acting in opposition to each other, a rheostat for each circuit, and an electromagnet in each circuit controlling the rheostat for the other circuit.

45 11. In an electric elevator, the combination of the car, a counterweight overbalancing the car, an actuating-machine having a main circuit and a local short circuit opposing the main circuit, resistances in each circuit and means for controlling the resistances from the car, substantially as described.

60 In witness whereof I subscribe my signature in presence of two witnesses.
